TOE IRON

Theodore Elliott, Winchester, Mass.

Application June 10, 1938, Serial No. 212,923

5 Claims. (Cl. 280—11.35)

This invention relates to the art of skiing and is particularly concerned with the problem of suitably attaching the skier's shoe to the ski.

In attaching shoes to skis, the requirements are simple. The shoe must be so held that it may be readily flexed as the skier takes a forward step but at the same time it must be secured in such a way that there will be no lateral motion between the shoe and the ski. This is essential if proper control is to be had. In addition, the area on which the sole of the shoe rests must be ample to prevent distortion of the sole.

It is customary to provide a clamping means of some sort to hold the forward part of the shoe sole firmly in position on the ski while it is urged forwardly by some sort of flexible binder, fastener or strap means which at the same time permits raising of the heel. One of the commonest forms of toe clamping means or toe irons, as they are commonly called, is a channel-shaped member having its sides converging forwardly. In this channel the sole of the shoe may be wedged and held in position by the forward pressing binder means about the heel. A strap usually runs from one side of the toe iron to the other over the shoe toe to prevent the shoe from slipping upwardly out of position.

Due to the varying sizes and shapes of skier's shoes, it has been found desirable to make the toe irons adjustable laterally so that they may fit various size shoes.

One of the objects of my invention is, therefore, to provide a toe iron which may be adjusted to fit shoes of various sizes and shapes and at the same time provide the firm and adequate support that is essential.

Another object of my invention is to provide a toe iron which may be adjusted in small increments easily and without undue loss of time.

A still further object of my invention is to provide a toe iron which not only has the foregoing advantages but also is made simply and ruggedly so that it may withstand the severest use to which it may be put.

These and other advantages of my invention will appear as the description proceeds with the aid of the accompanying drawing in which

Fig. 1 is a plan view of my toe iron as it appears installed on a ski.

Fig. 2 is an elevation of my toe iron looking from the rear.

Fig. 3 is a section on the line 3—3 of Fig. 2.

Fig. 4 is a plan view of my toe iron showing one cover plate and one side plate removed.

Fig. 5 is a plan view of one of the cover plates.

Fig. 6 is an elevation of the cover plate shown in Fig. 5.

Referring now to Fig. 1, 2 is a ski of the usual construction to which my toe iron is to be secured. The toe iron consists of but five parts, a base plate 4, the side plates 6 and 8, and the cover plates 10 and 12.

Base plate 4 at its forward and rear edges has upturned flanges 14 and 16 which, on their inner edges, are provided with notches or teeth 18 and 20.

These teeth may extend continuously from one side of the base plate to the other or they may be discontinuous as shown in Fig. 1. It is merely necessary that there be sufficient teeth to provide the desired range of adjustment. Base plate 4 is preferably made of fairly heavy gauge metal, sufficiently strong to withstand any loads that may be applied, and for best results should be plated or of stainless steel, as should all of the parts.

The side plates 6 and 8 are constructed to be mounted on the base plate 4 within the upturned flanges 14 and 16. Each side plate, as can be readily seen from the drawing, is made of sheet metal formed at substantially a right angle to provide a horizontal portion 22 which is in engagement with the base plate and a substantially vertical side wall 24 against which the side of the shoe is wedged.

The horizontal portion 22 of each side plate has its front and rear edges provided with notches or teeth 26 and 28 which are adapted to engage with teeth 18 and 20 of the base plate. Teeth 26 and 28, however, are formed on arcs of a circle the diameter of which is equal to the distance between flanges 14 and 16. By this arrangement, it is obvious that side plates 6 and 8 may be set in a large number of different positions between flanges 14 and 16, and still by virtue of the engagement with the teeth be held securely against lateral movements.

This construction makes it possible for side walls 24 to be moved closer together or farther apart as desired, and at the same time the angularity of each wall may be varied individually.

In base plate 4 there are a plurality of holes 30 through which securing screws are adapted to pass. The horizontal portions 22 of the side plates 6 and 8 have been cut away, as at 32, to provide ample range of lateral movement with respect to the screws.

Overlying the horizontal portions 22 of the side plates, which in turn are resting on the base plate 4, are the two cover plates 10 and 12. These

55

cover plates are complementary and the forward and rear ends have downwardly turned flanges 38 and 40 which assist in securing the cover plates against longitudinal movement. The two cover plates together form a trapezoidal supporting surface of sufficient area to adequately support that part of the sole directly under the foot. The edges of the sole, in very large shoes, which might overhang the sides of the cover are under no direct vertical load and hence there is no distortion.

Each cover plate is perforated with holes corresponding to holes 30 in the base plate and the holes so formed have the metal bent downwardly as at 41 to provide rigidity as well as a countersunk area to take the head of an ordinary flathead screw.

After positioning the horizontal portions 22 as desired with respect to base plate 4, the cover plates 10 and 12 may be laid thereover to substantially cover the horizontal portions and may be secured by the introduction of screws through the registering holes in the cover plate and base plate. The side plates 6 and 8 will thereby be firmly fastened against any movement.

The cut-away areas 32 of the horizontal portions 20 and 22 are large enough so that there will be no engagement with the downwardly formed edges 41 of the screw holes of the cover plates. Nor do the edges 41 depend far enough to touch the base plate 4 when the unit is in secured position. That is to say, the horizontal portions 20 and 22 are held against lateral movement by the meshing of the teeth 18 and 26 while vertical movement is prohibited by the clamping action of base plate 4 and the two cover plates.

It should also be noted that when the horizontal portion 22 of either side plate is adjusted to the most inward position permitted by its accompanying cover plate, no part of the portion 22 will be covered by the other cover plate. That is to say, each horizontal portion 22 and its cover plate are disposed at all times on opposite sides of the line along which the cover plates abut. This is essential if each side plate is to be freely adjustable without disturbing the other.

On the side walls 24 of the side plates 6 and 8 are means for controlling the location of the flexible tensioning means that is customarily used to force the shoe forwardly into the toe iron. A lip 42 is punched outwardly from each of the side walls 24 and this lip provides a stop against which the flexible means will upwardly engage as the heel is raised.

A second provision for engaging the flexible means is supplied in the form of the downwardly bent tabs 44 at the rear of each of the side walls. Under certain conditions of skiing it is found desirable that the force exerted by the flexible means be directed somewhat lower, and when such conditions prevail, tabs 44 are pressed into use.

In applying my toe iron to the ski, the following procedure is used. The base plate 4 is positioned at the proper location for the ball of the foot and midway between the sides of the ski. The position is noted by marking on the ski through the screw holes in the base plate. At these points small holes may be drilled in the skis of a size adapted to subsequently receive the screws.

With the base plate thus located, the side plates 6 and 8 are set thereon in the approximate positions required to accept the skier's shoe. Cover plates 10 and 12 are then placed thereover and

screws 46 are inserted and screwed firmly in position binding the side plates firmly in place.

With the toe iron thus installed, the user may then insert his shoe and secure it by the usual flexible tensioning means. If, upon inspection, it appears that the side walls 24 of the toe iron are not spaced a proper distance apart or are at an incorrect angle, adjustment may readily be made by removing first one cover plate, as for example 12, and adjusting side plate 6. Thereafter, when cover plate 12 has been resecured cover plate 10 may be removed and suitable adjustment made to the other side plate 8.

The ability to adjust either side plate individually without in any way disturbing the adjustment or fastening means of the other side plate, base plate or cover plate, is of distinct advantage, and such independent adjustability, as far as I am aware, is not provided in any toe irons made heretofore. While I have pointed out a preferred form of my invention, I desire it to be understood that I do not intend to be limited by the specific construction disclosed but only by the appended claims.

I claim:

1. A toe iron comprising a base plate having oppositely disposed flanges, a pair of side plates having horizontal portions positioned on said base plate and between said flanges, means on said base plate and on said horizontal portions for adjustable engagement therebetween, and a cover plate comprising two parts, one part overlying the horizontal portion of one side plate, the other part overlying the horizontal portion of the other side plate and means for binding said base plate, horizontal portions and cover plates against a ski, whereby one of said cover plates may be removed to permit individual adjustment of one side plate without disturbing said other side plate.

2. A toe iron comprising a base plate having oppositely disposed flanges, a pair of side plates having horizontal portions adapted to be positioned on said base plate, means for adjustable engagement between said base plate flanges and said horizontal portions, and an individual cover plate for each of said horizontal portions for independently locking each portion between said base plate and said cover plate whereby one side plate may be adjusted without disturbing the adjustment of said other side plate.

3. A toe iron comprising a base plate having raised teeth at its front and rear ends, a pair of side plates each having a horizontal portion with teeth on the front and rear edges, said portions adjustably positioned on said base plate with said teeth engaging said raised teeth at both the front and rear, said portions being wholly disposed on either side of a medial line extending between the said raised teeth, and means for independently locking each horizontal portion in position on said base plate comprising a pair of cover plates, said cover plates disposed on opposite sides of said medial line, and together forming a trapezoidal bearing surface, registering holes through said base plate, horizontal portions and cover plates, whereby they may be screwed to a ski and whereby the cover plate and side plate on one side of said medial line may be removed and adjusted without disturbing the setting or securing means of said other side plate.

4. A toe iron comprising a base plate having integral upturned parallel end flanges with teeth on their opposed faces, a pair of side plates each having a horizontal portion with oppositely disposed teeth for engagement with said flange

teeth, a pair of complementary cover plates adapted to overlie and bind said horizontal portions when the latter are in position on said base plate, common means for securing said parts together, the engagement between said cover plates and horizontal portions being distributed over a substantial area remote from said securing means, and each horizontal portion being disposed under only one of said cover plates.

5 10 5. A toe iron comprising a base plate, a pair of side plates having portions connected thereto

adapted to be positioned on said base plate, means whereby said portions may be adjusted in relation to said base plate comprising means oppositely disposed on said base plate and cooperating means on said portions, and an individual cover plate for each of said portions for independently locking each portion between said base plate and said cover plate whereby one side plate may be adjusted without disturbing the adjustment of said other side plate.
